UNITED STATES PATENT OFFICE.

JENS G. SCHREUDER, OF EDGEWOOD PARK, PENNSYLVANIA, ASSIGNOR TO THE UNION SWITCH AND SIGNAL COMPANY, OF SWISSVALE, PENNSYLVANIA.

SIGNAL.

SPECIFICATION forming part of Letters Patent No. 606,429, dated June 28, 1898.

Application filed February 21, 1898. Serial No. 671,105. (No model.)

To all whom it may concern:

Be it known that I, JENS G. SCHREUDER, a subject of the King of Sweden and Norway, residing at Edgewood Park, in the county of 5 Allegheny and State of Pennsylvania, have invented or discovered certain new and useful Improvements in Signals, of which improvements the following is a specification.

The invention described herein relates to 10 certain improvements in semaphore-signals for railways, and has for its object a construction of signal and its controlling or operating means whereby the signal will be returned automatically to normal or danger 15 position from caution or clear positions.

The invention is hereinafter more fully described and claimed.

In the accompanying drawings, forming a part of this specification, Figure 1 is an elevation of a semaphore-signal having my improvement applied thereto. Fig. 2 is a top plan view of the same. Fig. 3 is a sectional view, on an enlarged scale, of the automatic mechanism for returning the signal to normal 25 position. Fig. 4 is a view in elevation of the automatic mechanism, the inclosing case or shell being removed. Fig. 5 is a transverse section on the line V V, Fig. 3. Fig. 6 is a detail view of the signal-blade casting. 30 Figs. 7 and 8 are views in elevation, illustrating a modification of my improvement; and Fig. 9 is a sectional elevation of the operating mechanism.

In the practice of my invention a plate 1, 35 provided with a projecting boss 2, which forms a bearing for the semaphore, is bolted or otherwise secured to the signal-post 3. A shaft or pivot-pin 4 is secured to the plate 1, with its axis in line with the center of the boss 2, and 40 on the shaft or pin is mounted the semaphore-casting 5, which is provided on one side with a socket or seat 6 for the reception of one end of the blade 7 and on the opposite side with rings or spectacle-frames 8 for the reception of lenses for night-signaling. The 45 semaphore-casting is so constructed that the spectacle-frame will counterbalance or nearly counterbalance the blade 7 when secured to the casting. It is preferred to interpose anti-50 friction-balls 9 between the boss 2 and the semaphore-casting, which is provided with an

annular flange 10, adapted to fit closely over the boss 2 and protect the bearing.

One or more lugs or projections 11, having their edges beveled or inclined, are formed or secured on the outer face of the semaphore-casting eccentric to its center of movement or pivotal support. A block 12, having one or more lugs or projections 13, with their edges similarly beveled or inclined, is placed on the pin or shaft 4. The lugs or projections 11 and 13 are so constructed as to fit between each other, with their beveled or inclined edges bearing against each other. The block 12 is held from rotation on the pin or shaft, but 60 with a freedom of longitudinal movement along it, by any suitable means—for example, making the portion of the shaft or pin on which the block is mounted angular in cross-section and the opening through the block 70 of corresponding shape, as clearly shown in Fig. 3. The block is yieldingly held from movement along the pin or shaft 4 by a spring 14, bearing at one end against the block and at the opposite end against a washer 15, secured on the pin or shaft or other stationary abutment. These several parts are protected by a shell 16, as shown in Fig. 3.

It is characteristic of my improvement that when the signal, which is designed to be 80 shifted by the usual or any suitable connections to an operating-lever, is moved to either clear or caution position the block will be forced along the pin or shaft, compressing the spring by the sliding of the beveled edges 85 of the lugs 11 on the edges of the lugs 13. When the signal is free to move, the compressed spring will push the block inwardly and the wedge-like action of the lugs 13 on the lugs 11 will cause the signal to return to 90 normal position.

In Figs. 7 and 8 I have shown a modified form in which a spring is placed under tension by the shifting of the signal from normal position and its tension utilized for returning 95 it to such position.

In the construction shown in Figs. 7 and 9 a spring 14 is arranged around the signal-rod 17, and bears at its ends against two abutments 18 and 18^a, which are movable to compress the spring in one direction, but are held as against any movement in the opposite di-

rection. These abutments are preferably constructed in the form of sleeves fitting around the rod 17, and one of them, as 18, is supported or held stationary by a socket 19, 5 forming the lower end of the shell or cylinder 20. The other sleeve bears against one end of a shell 20, secured to the signal-post, and serves as a guide for the sleeves. On the signal-rod are secured collars 21 21^a, adapted 10 to bear against and shift the sleeves. If a down-pull be exerted on the signal-rod to shift the signal to caution position, the collar 21 will force the sleeve or abutment 18 downward, compressing the spring, which will be- 15 come effective to return the signal to normal position when free to move. If the rod 17 be moved up to clear the signal, the sleeve 18^a will be shifted and the spring compressed.

As shown in Fig. 8, this device may be applied to a signal independent of the operating-rod, the rod 17^a being connected to the blade on the side of its pivotal point opposite to that to which the operating-rod is connected.

I claim herein as my invention—

25 1. The combination of a semaphore-signal, mechanism for shifting the signal to clear and caution positions and a mechanism operative on the signal at one side of its pivotal support for automatically shifting the signal from 30 both clear and caution positions to normal position, substantially as set forth.

2. The combination of a semaphore-signal,

mechanism for shifting the signal to clear and caution positions and a mechanism connected to the signal on one side of its pivotal support and rendered operative by the shifting of the signal for automatically returning the signal from both clear and caution positions to normal position, substantially as set forth. 35

3. The combination of a semaphore-signal, 40 mechanism for shifting the signal to clear and caution positions and a spring connected to the signal at one side of its pivotal support and adapted to be placed under tension by the movement of the signal to clear and caution 45 positions, whereby it is rendered operative to return the signal, when free to move to normal position, substantially as set forth.

4. The combination of a semaphore-signal provided with an inclined bearing-surface at 50 one side of its pivotal support, a non-rotatable block provided with a correspondingly-inclined bearing-surface, a spring for yieldingly holding the inclined surfaces against each other and means for shifting the signal 55 to clear and caution positions, substantially as set forth.

In testimony whereof I have hereunto set my hand.

JENS G. SCHREUDER.
